UNITED STATES PATENT OFFICE.

CARL TILGER AND PETER BRENNER, OF DUSSELDORF, GERMANY.

COVER-FASTENING FOR POTS.

SPECIFICATION forming part of Letters Patent No. 508,066, dated November 7, 1893.

Application filed July 24, 1893. Serial No. 481,279. (No model.)

To all whom it may concern:

Be it known that we, CARL TILGER and PETER BRENNER, subjects of the German Emperor, residing at Dusseldorf, Germany, have 5 invented certain new and useful Improvements in Cover-Fastenings for Pots, with description as follows.

This invention relates to an improved cover fastening for pots, which consists of two or 10 more spring bolts secured to the cover and adapted to engage a shoulder on the pot.

In the accompanying drawings: Figure 1 is an elevation partly in section of our improved cover fastening; Fig. 2 a bottom view of the 15 cover; Fig. 3 a section on line x, x , Fig. 1; Fig. 4 an elevation partly in section of the cover fastening, with the bolts shot outward; Fig. 5 a similar view of part of the fastening with the bolt withdrawn.

20 The letter A, represents a pot or vessel of suitable construction and having an inwardly projecting shoulder or socket n , formed within its neck.

The lid or cover B is provided with two or

more radial sockets a , containing bolts b , the 25 shanks of which are surrounded by springs f . The heads of the bolts may be either pointed or beveled. When the cover is pressed down, the spring bolts will, after clearing the shoulder n , shoot outward, and thus hold the cover 30 in position. When the cover is raised, the bolts will be automatically forced inward to clear the shoulder. Thus, the cover may be readily raised and lowered and will be securely held to its seat by the bolts. 35

What we claim is—

The combination of cover B, having sockets a , and spring bolts b , with a pot A, having a shoulder n , adapted to be engaged by the bolts, substantially as specified. 40

In testimony whereof we have signed this specification in the presence of two subscribing witnesses.

CARL TILGER.
PETER BRENNER.
